A. PETROV.

PUMP.

APPLICATION FILED DEC. 23, 1919.

1,341,194.

Patented May 25, 1920.

UNITED STATES PATENT OFFICE.

ARTHUR PETROV, OF WAPELLA, SASKATCHEWAN, CANADA.

PUMP.

1,341,194.

Specification of Letters Patent. Patented May 25, 1920.

Application filed December 23, 1919. Serial No. 346,930.

To all whom it may concern:

Be it known that I, ARTHUR PETROV, of the town of Wapella, in the Province of Saskatchewan, Canada, have invented certain new and useful Improvements in Pumps, of which the following is the specification:

The invention relates to improvements in pumps, particularly as associated with wells and the principal object of the invention is to provide a pump whereby one can pump water from the well with a minimum amount of work, a special feature being that the ordinary reciprocating handle is entirely dispensed with and a hand wheel provided which when properly manipulated with other parts does the required work.

A further object of the invention is to construct the pump in a simple, inexpensive and durable manner and such that it can be readily installed and can be relied upon to effectively do its work.

With the above general objects in view the invention consists essentially in the arrangement and construction of parts hereinafter more particularly described and later pointed out in the appended claims, reference being had to the accompanying drawing in which:

30. Figure 1 is a vertical sectional view through a well showing my invention installed.

Fig. 2 is a horizontal sectional view at 2-2' Fig. 1 and looking downwardly.

35. Fig. 3 is a horizontal sectional view through the well at 3-3' Fig. 1.

Fig. 4 is an enlarged vertical sectional view through the valve.

In the drawing like characters of reference indicate corresponding parts in the several figures.

1 represents the well which is suitably lined by boards 2 or similar facing pieces preventing the dirt from falling in. The top of the well is closed by a platform 3 and at the bottom of the well I locate a centrally disposed vertically extending cylinder 4 having the upper end open and the bottom end closed as shown at 5. The cylinder is held in a fixed position in the bottom of the well by suitably disposed fastening brackets 6 attached to the cylinder and the well lining.

7 is a plunger mounted for reciprocating

movement within the cylinder and 8 is a valve attached to the lower end of the cylinder and arranged to permit of the passage of water inwardly to the cylinder and to close upon a back pressure being developed in the cylinder by the down movement of the piston. The details of this valve are not herein enlarged upon, it being simply a flap valve as clearly shown in Fig. 4.

The plunger is carried by a vertically extending centrally positioned hollow pipe or tube 9 extending upwardly toward the top of the well and connected by a T-pipe 10 to the lower end of a jack screw 11 and to a discharge pipe 12 more or less of an L-shape. The jack screw and the discharge pipe pass freely through the platform and at the upper end of the jack screw I locate a box 13 loaded with stones or similar weights 14. A tap 15 is provided at the upper end of the discharge pipe and if desired a flexible hose 16 can be attached to allow of the directing of the water discharged. The pipe 9 is suitably guided for sliding movement in a bearing 17 carried by brackets 18 similar to those shown at 6. 19 is a head plate carried by suitable legs 20 bolted to the platform. The jack screw passes freely through the head plate and the head plate is utilized as a working bearing for a comparatively large hand wheel 21 operatively mounted on the jack screw and provided with a comparatively heavy rim.

When one desires to pump water with this appliance he closes the tap 15 and turns the hand wheel in one direction, say a clockwise direction, which action causes the jack screw to rise against the action of the weight 14 and in rising it pulls up the plunger and draws water into the cylinder through the valve 8.

Obviously as the jack screw and pipe 9 go up the discharge pipe goes up and for this reason it is desirable to have a flexible connection such as a hose 16 to control the water when later discharged.

When one is ready to discharge the water he opens the valve and then gives the hand wheel a quick turn in the reverse direction or a counter-clockwise direction and if the wheel is pulled quickly it will spin up the jack screw away from the plate 19, the upward movement of the hand wheel being

quicker than the down movement of the jack screw acting under the action of the weight 14.

Obviously as soon as there is a clearance 5 between the hand wheel and the head plate the weight acts to force the plunger down with the result that the valve 8 closes and the water is discharged up the pipes 9 and 12 and out the hose, provided of course the 10 tap is opened. If however, the tap is not opened the water trapped in the cylinder will hold the weight in the box so that one can draw water any time he opens the tap provided the weight box is up and the hand 15 wheel is away from the head plate.

From the above it will be apparent that this provides a very easy arrangement for pumping water as it requires little effort on the part of the operator, the pumping being 20 actually done by the weight and all the operator has to do is to first turn the hand wheel in one direction and then give it a quick turn in the other.

By providing a heavy rim to the hand 25 wheel it acts in the nature of a fly wheel and will spin up from the plate if it is given a good pull to start with.

What I claim as my invention is:—

1. In a well, a stationary cylinder located 30 in the base of the well, a normally closed intake valve connected to the lower end of the cylinder, a piston operatively mounted within the cylinder, a hollow main pipe connected to the cylinder and extending upwardly within the well, an offset discharge pipe connected to the former pipe, a valve controlling discharge through the discharge pipe, a weighted jack screw connected to the main pipe, a stationary head plate surrounding the jack screw and operating means screw threading on to the jack screw and normally bearing on the head plate and designed when turned in one direction to raise the jack screw and parts connected thereto.

2. In a well, a stationary cylinder located 35 in the base of the well, a normally closed intake valve connected to the lower end of the cylinder, a piston operatively mounted within the cylinder, a hollow main pipe connected to the cylinder and extending upwardly within the well, an offset discharge pipe connected to the former pipe, a valve controlling discharge through the discharge pipe, a weighted jack screw connected to the main pipe, a stationary head plate surrounding the jack screw and a hand wheel mounted on the jack screw above the head plate.

60 3. In a well, a stationary cylinder located

in the base of the well, a normally closed intake valve connected to the lower end of the cylinder, a piston operatively mounted within the cylinder, a hollow main pipe connected to the cylinder and extending upwardly within the well, an offset discharge pipe connected to the former pipe, a valve controlling discharge through the discharge pipe, a weighted jack screw connected to the main pipe, a stationary head plate surrounding the jack screw and an operating hand wheel operatively mounted on the jack screw above the head plate and provided with a comparatively heavy rim.

4. In a well, a stationary cylinder located 75 in the base of the well, a normally closed intake valve connected to the lower end of the cylinder, a piston operatively mounted within the cylinder, a hollow main pipe connected to the cylinder and extending upwardly within the well, an offset discharge pipe connected to the former pipe, a valve controlling discharge through the discharge pipe, a vertically extending jack screw extending out of the well and having the lower 80 end permanently connected to the upper end of the main pipe, a comparatively heavy weight located at the upper end of the jack screw, a permanently supported bearing plate surrounding the jack screw and an operating hand wheel operatively mounted on a jack screw in a location above the plate.

5. In a well, a cylinder permanently fixed 85 in the bottom of the well and having a closed lower end, a normally closed inlet valve 90 located at the bottom of the cylinder, a piston operatively mounted for reciprocating movement within the cylinder, a main vertically extending water pipe carrying the plunger and opening to the interior of the 100 cylinder through the plunger, an offset discharge pipe communicating with the upper end of the main pipe and extending out of the well, a valve controlling discharge from the upper end of the discharge pipe, a jack 105 screw vertically aligned with the main pipe and permanently connected thereto and extending upwardly out of the well, a weight box mounted on the upper end of the jack screw, a permanently supported bearing 110 plate surrounding the jack screw outside the well and a hand wheel operatively mounted on the jack screw above the bearing plate.

Signed at Winnipeg, this 25 day of November 1919.

ARTHUR PETROV.
